MEANS FOR COOLING ELECTRIC APPARATUS

Application filed September 13, 1929. Serial No. 392,421.

In electric apparatus there are various unavoidable losses such as core losses and electrical resistance losses. The energy expended by such losses within the apparatus appears in the form of heat energy. The rate at which the heat developed by these losses in the apparatus is removed therefrom is a factor in the determination of the capacity or continuous rating of the apparatus, and it is a purpose of my invention to provide a means for removing the heat developed in such apparatus.

In general, stationary electrical apparatus such as transformers comprise a tank in which the induction coils are submerged in insulating oil. During the operation of the apparatus, the heat developed by the core and the coils is transferred to the oil in contact therewith. The oil thus heated rises to the top of the tank, moves toward the walls of the tank to which the heat absorbed from the coils is transferred, and descends to the bottom of the tank to again come in contact with the coils, taking the place of oil which was heated and moved upwardly. Thus, a continuous circulation of the oil takes place within the casing transferring the heat developed in the winding to the walls of the tank from which it is transferred to the surrounding medium. In some cases conduits have been provided which extend from the top of the tank to the bottom thereof and through which the oil circulates. The conduits present a larger surface to the atmosphere which circulates between the conduits and the tank. In other instances, the oil in the tank is water cooled, the oil being continuously circulated through coils which are cooled by water to which the heat is transferred. This method of cooling requires expensive auxiliary apparatus and an abundant supply of water.

By my invention, I cool electrically apparatus by expending the heat energy developed therein in the evaporation of moisture. I employ a construction in which air charged with entrained moisture is circulated in contact with the outer surface of the walls of the casing enclosing the electrical apparatus.

Specifically, I provide a housing which sur-

rounds the tank or casing of the stationary electric apparatus. The housing is so located with respect to the walls of the tank that a passage is provided around the tank for a circulating medium. Inlet and outlet openings are provided in the walls of the housing and are so located that air flowing from one to the other is caused to circulate around the tank of the induction apparatus. A fan is mounted within the housing to cause air to flow therethrough by way of said openings. Adjacent the inlet to the housing, I provide a spray forming device for introducing moisture in the form of finely divided particles into the air entering the housing. Foraminous partition walls transverse to the direction of movement of the air are located within the housing behind the spray forming device relative to the direction of movement of the air through the housing. These foraminous partition walls through which the air is caused to flow, are maintained in a moist condition, thereby providing a large wetted area from which moisture may be evaporated.

I shall now describe one embodiment of my invention in connection with the accompanying drawing in which:

Fig. 1 is a side elevation of a stationary induction apparatus with the outer housing in section, the outer electric bushings etc. not being shown;

Fig. 2 is a transverse section of the same taken on the line 2-2 of Figure 1.

The embodiment of this invention as illustrated comprises a stationary induction apparatus 1, such for example as an ordinary transformer, which consists of a tank or casing in which the core and the coils wound thereon are submerged in oil. Surrounding the tank is a housing 2.

The housing 2 is spaced from the transformer tank 1 to provide a passage between the housing and the outer wall of the tank. The housing may be constructed of sheet metal formed to the desired shape, in this instance cylindrical. By constructing the housing in two parts, as shown, it may be readily assembled about the transformer, the edges of the parts being bent outwardly to form flanges 3 for securing the parts together by 100

means of bolts or the like. In both halves of the housing at the center of the surface thereof, openings 4 and 5 are provided which in the assembled structure constitute opposed 5 inlet and outlet openings respectively. The metal around the openings 4 and 5 is flared outwardly forming circular flanges 6 which with the screens 7 covering the openings from a bell-shape housing for fan motors 8, 10 mounted at each opening. In certain cases only one motor fan may be used as desired. In such construction the single motor is preferably mounted at the inlet opening in the housing.

15 The motors 8 are centrally mounted in the bell-shape housings formed on the sides of the housing 2, and are supported therein by circular screen supports 9 and 10 which are secured at the outer edge to the housing and 20 at the inner edge to the bearings of the motor. On the extended end of the motor shafts adjacent the screen covered openings in the housing 2, fans 11 are secured which, when the motors are operating, force air through 25 the housing by way of the inlet 4 and outlet 5.

At the inlet opening 4, a spray forming device 12 is directed toward the fan 11. The sprayer has a conduit 13 connected there- 30 to which extends through the screen 7 to a source of fluid supply (not shown). The sprayer 12 introduces moisture into the incoming air in the form of finely divided particles which is partly evaporated by the air 35 and partly carried as entrained moisture in the air. A suitable valve 14 may be provided between the supply conduit 13 and the sprayer 12 for regulating the quantity of moisture introduced into the air.

40 Within the housing, radial screens 15 extending between the housing and the transformer tank, are provided. The first set of screens are angularly displaced through an angle of approximately 45° on opposite sides 45 of the longitudinal plane containing the centers of the inlet and outlet openings, the second set of screens being displaced through an angle of 90° on opposite sides of the same plane. Upon the screens 15 entrained moisture carried by the air flowing through the casing is deposited and maintains the screens in a moist condition. The excess moisture deposited on the screens 15 is drained from 50 the housing through the drain 16 provided therefor.

55 The operation of the device above described is as follows: The heat developed in the coils and core of the transformer during the operation thereof is transferred by the circulation 60 of the oil therein to the walls of the tank. The fan motors 8 are operated, the fans 11 causing air to flow through the housing 2 by way of the openings 4 and 5. At the opening 4, moisture is introduced into the air entering the housing 2 by the spray forming de-

vice 12. Part of the moisture introduced into the air at the inlet 4 is evaporated by the air, the evaporation being caused by the expenditure of heat energy in the air, thereby cooling the air. A portion of the moisture not 70 evaporated by the heat of the air is carried entrained in the air and is evaporated by heat taken from the wall of the transformer tank. The remainder of the moisture carried by the air is deposited upon the screens 15 within the casing and maintains the screens in a wet condition forming efficient evaporation areas. Thus, heat is absorbed from the tank by evaporation of moisture carried by the air and is transferred to the air which is cooled by the evaporation of moisture at the inlet and at the wet screens 15. The air after absorbing the heat of this tank is then exhausted through the opening 5. Excess moisture deposited in the casing is drained therefrom by a suitable drain 16.

80 In cooling by evaporation as is done in the construction shown in the drawing and above particularly described, the quantity of water required to cool the mechanism is much less than that required in constructions in which the mechanism is cooled by the transfer of heat to the cooling water. The reason a much less quantity of water is required in cooling by evaporation is the fact that 970 B. t. u. 90 are required to evaporate one pound of water, whereas when the heat is transferred to the cooling water to raise the temperature thereof, only one B. t. u. is absorbed by a pound of water for each degree rise in temperature.

95 It will be readily apparent to those skilled in the art that I have devised a cooling device for electrical apparatus that is efficient in operation, requires only a relatively small fluid supply and is simple in construction.

100 It is obvious that various changes may be made in the illustrated embodiment above particularly described within the principle and scope of my invention as expressed in the appended claims.

110 I claim:

115 1. Means for cooling a tank containing electrical apparatus comprising, a housing surrounding and enclosing the tank and spaced therefrom to provide a passage between the tank and the housing, said housing having inlet and outlet openings therein, means for causing air to flow through the inlet in the housing and around the tank to the outlet in the housing, and means adjacent the inlet in the housing and in advance of the air moving means relative to the direction of movement of the air for introducing moisture into the air flowing therethrough.

120 2. A cooling device for a tank containing electrical apparatus comprising, a housing surrounding and enclosing said tank and spaced therefrom to provide a passage between the tank and the housing, the housing having inlet and outlet openings therein,

means for causing air to flow through the inlet in said housing and around said tank to the outlet in the housing, transverse screens in said housing, and means for maintaining the screens in a wet condition.

3. A cooling device for a tank containing electrical apparatus comprising, a housing surrounding and enclosing the tank and spaced therefrom to provide a space between 10 the housing and the tank, said housing having inlet and outlet openings therein, means for causing air to flow through the inlet in the housing and around the tank to the outlet in the housing, transverse screens in said 15 housing, and means adjacent the inlet in the housing for introducing moisture into the air flowing through the housing.

4. A cooling device for a tank containing electrical apparatus comprising, a housing 20 surrounding and enclosing said tank and spaced therefrom, said housing having inlet and outlet openings therein, a fan within said housing for causing air to flow through the inlet in the housing and around the tank to 25 the outlet in the housing, transverse screens in said housing, and a spray forming device adjacent said inlet for introducing moisture into the air flowing therethrough.

5. A cooling device for a tank containing 30 electrical apparatus comprising, a housing surrounding and enclosing the tank and spaced therefrom, said housing having inlet and outlet openings therein, a fan within said housing adjacent the inlet opening there- 35 in, means for driving said fan to cause a current of air to flow through the inlet in the housing and around the tank to the outlet in the housing, and means adjacent the inlet in the housing for introducing moisture into 40 the air flowing therethrough.

6. A cooling device for a tank containing 45 electrical apparatus comprising, a housing surrounding and enclosing the tank and spaced therefrom, said housing having inlet and outlet openings therein, fans within said housing adjacent the inlet and outlet openings 50 therein, means for driving said fans to cause a current of air to flow through the inlet in the housing and around the tank to the outlet in the housing, and means adjacent the inlet in the housing for introducing moisture into the air flowing therethrough.

7. A cooling device for a tank containing 55 induction coils comprising, a cylindrical housing surrounding and enclosing the tank and spaced therefrom, said housing having opposed inlet and outlet openings therein, bell-shape motor housings extending from 60 said housing at the openings therein, motors mounted within said bell-shape housings, fans mounted on said motors for causing air to flow through the inlet in the housing around the tank to the outlet, and means adjacent the inlet for introducing moisture 65 into the air flowing through the inlet.

8. A cooling device for a tank containing induction coils comprising, a cylindrical housing surrounding and enclosing the tank and spaced therefrom, said housing having opposed inlet and outlet openings therein, bell- 70 shape motor housings extending from said housings at the openings therein, motors mounted within said bell-shape housings, fans mounted on said motors for causing air to flow through the inlet in the cylindrical housing 75 and around the tank to the outlet in the housing, screens within the cylindrical housing transverse to the direction of movement of the air therein, and a spray forming device adjacent the inlet for introducing moisture 80 into the air flowing therethrough.

9. Means for cooling encased electrical apparatus comprising a housing enclosing the casing and spaced therefrom to form a passage between the casing and the housing, the 85 housing having inlet and outlet openings therein, means for causing air to flow through the inlet in the housing and around the casing to the outlet in the housing, and means at the inlet to said housing, in advance of the 90 means for causing air to flow through the housing relative to the direction of motion of air through the housing, for introducing moisture into the air flowing through the housing. 95

10. Means for cooling encased electric apparatus comprising a housing enclosing the casing about the electric apparatus and spaced therefrom to form a passage between the casing and the housing, the housing having inlet and outlet openings therein, means for causing air to flow through the inlet in the housing and around the casing to the outlet in the housing, foraminous partitions within the housing transverse to the flow of air therethrough, and means for maintaining the foraminous partitions in a wet condition. 100
